Attorney

UNITED STATES PATENT OFFICE

HARRY R. McDONALD, OF DUNKIRK, INDIANA

PAPER HOLDER

Application filed September 27, 1930. Serial No. 484,774.

It is the object of my invention to provide a paper-weight under which sheets of paper can be easily inserted and as easily withdrawn, but which will hold papers firmly while in use. It is a further object of my invention to provide a paper holder in which the paper-weight is held in position so that it will be unnecessary to handle that weight to effect the insertion of papers under it or the withdrawal of papers from under it whereby the insertion and/or withdrawal of papers may be effected by the use of only one hand; which paper holder is simple and convenient to use, and inexpensive of construction.

15 To this end, I provide a weight rollable in at least one direction, and a retaining member for the rollable weight which will prevent the weight from rolling out of position, but which will readily permit it to be lifted and 20 revolved by the insertion of even a thin sheet of paper thereunder or by the removal of paper therefrom.

Devices embodying my invention are illustrated in the accompanying drawings: Fig. 1 25 is a perspective view showing a preferred form of such a device; Fig. 2 is a side elevation of the device of Fig. 1, with parts broken away to show the action of the paper-weight; and Figs. 3, 4, and 5 are perspective views generally similar to Fig. 1, but with the rotatable weight in somewhat different forms and mountings.

In the preferred form of the device shown in Figs. 1 and 2 of the drawings; there is a 35 flat base 10 and a flat top 11 spaced from each other by a vertical wall 12 at one end of the device. The top member 11 is provided with a hole 13 just large enough to permit a spherical weight 14 to pass through it; and is spaced from the base member so that when the ball 14 is resting on that base member 10, the lower surface of the top member 11 is slightly above the center of the ball. This arrangement prevents the weight from ever becoming 45 wedged between the top and the base members, and insures that the weight will always be free to be lifted and to be rolled by the insertion of paper thereunder. This is clear 50 from Fig. 2 which shows in dotted-line posi-

tion the spherical weight with papers 15 in place under it.

In use, my device rests on a table or desk and has the rollable weight in position resting on the base member. When it is desired 55 to insert paper—either a single sheet or several sheets—into my paper holder, it is only necessary to push the paper between the ball and the upper surface of the base member. Such insertion of paper into the holder easily 60 lifts the ball and causes it to roll over the surface of the paper which is being pushed under it; for the ball is made of relatively light material and the position of the top member prevents any wedging action from being exerted 65 upon the ball by the top member.

When it is desired to remove paper from the paper holder, it is only necessary to grasp the paper and pull it out; for the ball freely 70 rolls over the surface of the paper as in the case of insertion of paper.

It is readily apparent that the rollable weight is the part of my device which holds the paper in place and that the other parts of the device serve to position the weight so 75 that it is never necessary to handle it in inserting papers under it, or to use more than one hand in manipulating the papers.

As I have said, Figs. 3, 4, and 5 show modifications of the device illustrated in Fig. 1. 80 Fig. 3 shows a paper holder which has a rollable weight in the shape of a cylinder 34, and the top member 31 of which has a rectangular hole 33 through it which is just large enough to permit the insertion of the cylindrical 85 weight.

In the device shown in Fig. 4, the rollable weight is a ring 44. Here also the hole through the top member 41 is a rectangular hole 43; which is just large enough to permit 90 the insertion of the ring, but which fits the sides of the ring especially closely for the purpose of constantly keeping the ring in upright position.

Fig. 5 shows a device which is very similar 95 to that of Fig. 3. Here the weight is a hollow cylinder 54, which instead of being inserted through a hole in the top member, is located in a rectangular cut-away portion 53 in the projecting end of the top member 51 100

and is held in place by a rod 55 which extends through the hollow cylinder and is mounted in those parts 56 of the top member which form the sides of the rectangular cut-away portion. The rod 55 is considerably smaller than the internal diameter of the cylinder, so that vertical movement of the cylinder is not prevented.

I claim as my invention:—

10. 1. A paper holder, comprising a base member, a top member spaced therefrom and having an opening through it, and a rollable weight adapted to loosely pass through said opening, said weight being restrained from horizontal movement by the bounds of said opening.
20. 2. A paper holder, comprising a base, a supporting pedestal extending upward from the base, and an overhanging top carried by the pedestal and extending laterally therefrom so that it has a free edge for at least a substantial part of its periphery, said overhanging part of said top having an opening through it, and a rollable member loosely mounted in said opening and normally resting on said base and projecting above said top.
30. 3. A paper holder, comprising a base, a supporting pedestal extending upward from the base, and an overhanging top carried by the pedestal and extending laterally therefrom so that it has a free edge for at least a substantial part of its periphery, said overhanging part of said top having an opening through it, and a rollable member loosely mounted in said opening and normally resting on said base and insertable from the top through said opening.
40. 4. A paper holder, comprising a base, a supporting pedestal extending upward from the base, and an overhanging top carried by the pedestal and extending laterally therefrom so that it has a free edge for at least a substantial part of its periphery, said overhanging part of said top having a circular opening through it, and a spherical rollable member loosely mounted in said opening and normally resting on said base and projecting above said top.
50. 5. A paper holder, comprising a base, a supporting pedestal extending upward from the base, and an overhanging top carried by the pedestal and extending laterally therefrom so that it has a free edge for at least a substantial part of its periphery, said overhanging part of said top having a circular opening through it, and a spherical rollable member loosely mounted in said opening and normally resting on said base and insertable from the top through said opening.
60. 6. In witness whereof, I have hereunto set my hand at Dunkirk, Indiana, this 23rd day of September, A. D. one thousand nine hundred and thirty.

HARRY R. McDONALD.
